United States Patent

Des. 238,660
Patented Feb. 3, 1976

238,660

WRISTWATCH

Roland Rueffli, Grenchen, Switzerland, assignor to
Montres Orfina, S.A., Grenchen, Switzerland

Filed June 4, 1974, Ser. No. 476,325

Term of patent 14 years

Int. Cl. D10—02

FIG. 1 is a front elevational view of a wristwatch showing my new design;

FIG. 2 is a left side elevational view thereof;

FIG. 3 is a right side elevational view thereof;

FIG. 4 is a rear elevational view thereof.

I claim:

The ornamental design for a wristwatch, substantially as shown.
